UNITED STATES PATENT OFFICE

148,395

DESIGN FOR AN ICE-CREAM FREEZER

Edmond J. Spence, Montclair, N. J., assignor to
Master Industries, Inc., New York, N. Y., a cor-
poration of New York

Application May 25, 1946, Serial No. 130,070

Term of patent 3½ years

(Cl. D67—3)

To all whom it may concern:

Be it known that I, Edmond J. Spence, residing in Montclair, in the county of Essex and State of New Jersey, have invented a new, original, and ornamental Design for an Ice-Cream Freezer, of which the following is a specification, reference being had to the accompanying drawing, forming a part thereof.

Figure 1 represents a perspective view of an ice-cream freezer showing my new design.

Figure 2 is a side elevation of the same.

The other side of the freezer (not shown) is substantially like the side which is shown without the finger control, operating handle and knob.

I claim:

The ornamental design for an ice-cream freezer, as shown and described.

EDMOND J. SPENCE.
